Primary Examiner—Jennifer Rivard(74) *Attorney, Agent, or Firm*—Fulbright & Jaworski L.L.P.(57) **CLAIM**

The ornamental design for a cosmetic container, as shown and described.

DESCRIPTION

FIG. 1 is a top perspective view of my design;

FIG. 2 is a bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a back view thereof.

The dashed lines are environmental structure forming no part of the claimed design. All other surface(s) or portion(s) of the embodiments of my design not shown in the figures or otherwise described in the specification form no part of the claimed design.
